UNITED STATES PATENT OFFICE.

EDWIN BOYCE, OF PINE BLUFF, ARKANSAS.

AUTOMOBILE SIGNAL.

Application filed September 1, 1923. Serial No. 660,630.

To all whom it may concern:

Be it known that I, EDWIN BOYCE, a citizen of the United States, residing at Pine Bluff, in the county of Jefferson and State 5 of Arkansas, have invented certain new and useful Improvements in Automobile Signals; and I do declare the following to be a full, clear, and exact description of the invention, such as will enable others skilled in 10 the art to which it appertains to make and use the same.

My invention relates to improvements in signals for automobiles and other vehicles, to indicate to pedestrians, crossing policemen, 15 and drivers of other vehicles, what direction is to be taken by the machine.

The principal object of the invention is to provide improved means for detachably connecting the signal to its carrying and operating member, in such manner that a broken signal can be easily and quickly detached and a new one substituted, or a new bulb inserted.

Another object is to provide a device of 25 the class described which, although rather simple and inexpensive, will be very desirable and will present an attractive appearance on a machine.

With the foregoing in view, the invention 30 resides in the novel subject matter herein-after described and claimed, the description being supplemented by the accompanying drawings.

Fig. 1 is a side elevation of the invention 35 showing front and rear signals upon an automobile, connected for simultaneous operation, by an arrangement of cable and pulleys.

Fig. 2 is a vertical transverse sectional view as indicated by line 2—2 of Fig. 1.

Fig. 3 is an enlarged side elevation partly in section.

Fig. 4 is an enlarged vertical sectional view.

Figs. 5 and 6 are horizontal sectional views on lines 5—5 and 6—6 of Fig. 4.

Fig. 7 is a side elevation of the signal carrier.

Fig. 8 is a horizontal sectional view on line 8—8 of Fig. 7.

In the drawings above briefly described, the numeral 1 designates a suitable bearing adapted to be secured in any desired manner to the cowl or other preferred part of an automobile. Passing rotatably through the bearing 1, is a shaft 2 which is preferably

of tubular form, to receive a socket member 3 for an electric light bulb 4 which is within the signal 5, said signal being here shown in the form of a globe of porcelain, glass or 60 other suitable material, said globe preferably having the contour of the human hand, with the index finger extended.

The upper end of the shaft 2 is provided with an outstanding annular flange 6 which 65 forms with said shaft, a carrier for the signal 5, said flange 6 being preferably provided with an upstanding annular flange 7 spaced inwardly from its edge for reception in a depending hollow neck 8 with which 70 the signal 5 is provided, said signal being provided with an internal lug 9 for reception in an external recess 10 in the flange 7, so that the carrier and signal may rotate in unison. 75

A retaining ring 11 surrounds the edge portion of the flange 6 and the adjacent end of the neck 8 and is provided on its lower edge, with an inwardly extending annular flange 12 which contacts with the lower side 80 of said flange 6. The ring 8 is rotatable with respect to the carrier 2—6 and provision is made whereby rotation of this ring, together with axial movement of the neck 8, will either connect the neck with the carrier 85 or disconnect the same, as occasion may require.

In the preferred form of construction, the neck 8 is provided with a plurality of circumferentially spaced external lugs 13 and the upper portion of ring 11 is provided with an internal groove 14 having entrance throats 14^a, through which the lugs 13 may pass, so that turning of the ring 11 to the proper extent will position said lugs in said 95 groove 13, thus firmly connecting the carrier and the signal.

In order to hold the ring 11 against accidental release and to also prevent jarring or rattling of the signal 5, I have provided 100 a resilient transversely corrugated ring 15 which I interpose between the outer edge portion of the flange 6 and the adjacent edge of the neck 8. This ring has a tendency to force upwardly on the neck 8, thus holding 105 the lugs 12 tightly against the upper side of the groove 13 and holding the flange 12 of the ring 11 frictionally against the lower side of the flange 6.

While any suitable provision could be 110 made for turning the shaft 2, to operate the signal 5, I prefer to secure a pulley 16 on

the lower end of said shaft and to engage said pulley with an operating cable 17 passing around suitable guides and operable by a suitable control 18 which may well be located at the instrument board of the machine. I prefer that the cable 17 shall also operate a rear signal 19 which may be connected with its operating shaft in the same manner as above described, but the mounting means for the rear signal shaft forms the subject matter of a separate application and is not therefore disclosed in the present case.

It will be seen from the foregoing, that I have provided a very effective means for quickly and easily attaching the signal to its carrier, which is very desirable when substituting a new signal for one which has become damaged, or when it is necessary to insert a new bulb in the socket 3.

As excellent results are obtainable from the details disclosed, they are preferably followed, but within the scope of the invention as claimed, numerous changes may be made.

I claim:

1. A device of the class described comprising a signal carrier of circular outline, a signal having a portion of similar outline at one side of said carrier, a retaining ring surrounding said carrier and the adjacent portion of the signal and having an inwardly extending flange contacting with the side of the former remote from the latter, said ring and signal having coacting connecting means engageable and releasable by relative axial and turning movements, and yielding means interposed between said signal and carrier and tending to force them away from each other to frictionally hold said retaining ring and signal against relative turning.

2. A device of the class described comprising a signal carrier of circular outline, a signal having a portion of similar outline at one side of said carrier, a retaining ring surrounding said carrier and the adjacent portion of the signal and having an inwardly extending flange contacting with the side of the former remote from the latter, said ring and signal having coacting connecting means engageable and releasable by relative axial and turning movements, and a resilient corrugated ring interposed between said signal and carrier and tending to force them away from each other to frictionally hold said retaining ring and signal against relative turning.

3. A device of the class described comprising a signal carrier having a circular socket, a signal having a circular portion re-

ceivable in said socket, said socket and signal having coacting connecting means engageable and releasable by relative axial and turning movements, and a resilient corrugated ring interposed between and yieldably contacting with the socket bottom and the adjacent portion of the signal to hold them against accidental relative turning.

4. A device of the class described comprising a structure as specified in claim 1; said carrier being rotatable, and coacting means on the carrier and signal for connecting them to turn as a single unit.

5. A device of the class described comprising a rotatable signal carrier having a circular outline and having a circular flange at one side spaced inwardly from its edge, said flange being provided with a peripheral recess, a signal having a circular neck surrounding said flange and provided with an internal lug received in said recess to connect the carrier and signal for rotation as a single unit, and means for holding said signal and carrier in assembled relation.

6. A device of the class described comprising a rotatable signal carrier having a circular outline and having a circular flange at one side spaced inwardly from its edge, said flange being provided with a peripheral recess, a signal having a circular neck surrounding said flange and provided with an internal lug received in said recess to connect the carrier and signal for rotation as a single unit, the exterior of said neck having circumferentially spaced lugs, and a retaining ring surrounding said carrier and neck and having an inwardly extending flange engaging said carrier, said ring being formed with an internal groove receiving said spaced lugs and with entrance throats to said groove.

7. As an article of manufacture, a signal globe adapted to contain an electric bulb, said globe having a hollow neck adapted for reception in a carrying socket, said neck being provided with circumferentially spaced integral lugs on its outer side for engagement with the socket.

8. An article of manufacture as specified in claim 7; together with an additional lug on the inner side of said neck, for the purpose set forth.

In testimony whereof I have hereunto set my hand in the presence of two subscribing witnesses.

EDWIN BOYCE.
